UNITED STATES PATENT OFFICE.

ARTHUR L. GARFORD, OF ELYRIA, OHIO, ASSIGNOR TO THE GARFORD
MANUFACTURING COMPANY, OF SAME PLACE.

DESIGN FOR A BICYCLE-SADDLE SEAT.

SPECIFICATION forming part of Design No. 29,717, dated November 22, 1898.

Application filed October 29, 1898. Serial No. 694,983. Term of patent 7 years.

To all whom it may concern:

Be it known that I, ARTHUR L. GARFORD, a citizen of the United States, residing at Elyria, in the county of Lorain and State of Ohio, having invented and produced a new and original Design for Bicycle-Saddle Seats, of which the following is a specification, reference being had to the accompanying drawings, forming a part thereof.

- o Figure 1 is a plan view of a bicycle-saddle seat, showing my new design. Fig. 2 is a side elevation thereof. Fig. 3 is a transverse sectional view on line 3 3 of Fig. 1. Fig. 4 is a transverse sectional view on line 4 4 of Fig. 1.
- o As shown in the drawings, the leading or material features of my design consist of a seat A, which is pear-shaped in general outline; but its broad rear end is divided into two equal wings C by a furcation B, which
- o extends forward for about one-half the entire length of the seat. The front end of this

furcation is substantially a semicircle, whose rear ends are merged at b with the oppositely curved sides b' b² of said furcation, which sides from this point curve toward each other ²⁵ and then away from each other, and their rear ends join and are merged at D with the correspondingly curved rear ends of said wings. The top surface of the seat curves downward at its marginal edges and at the ³⁰ marginal edges of the furcation.

Having described my invention, what I claim as new, and desire to secure by Letters Patent, is—

The design for a bicycle-saddle seat as here- ³⁵ in shown and described.

In testimony whereof I hereunto affix my signature in the presence of two witnesses.

ARTHUR L. GARFORD.

Witnesses:

FRED N. SMITH,
D. B. ANDREWS.
